COMBINED TISSUE DISPENSER AND LITTER CONTAINER FOR AUTOMOBILES

Warren Wilson, 4633 Roxbury Road,
Corona del Mar, Calif.

Filed Nov. 3, 1964, Ser. No. 82,445

Term of patent 14 years

(Cl. D58—12.6)

FIGURE 1 is a perspective view of a combined tissue dispenser and litter container for automobiles, embodying my new design, the cover of the litter compartment being shown in open condition in order to illustrate a removable litter container therein;

The dominant features of the design reside in the portions shown in full lines.

I claim:

The ornamental design for a combined tissue dispenser and litter container for automobiles, substantially as shown and described.
